UNITED STATES PATENT OFFICE.

WILLIAM WALLACE CAMPBELL, OF YOKOHAMA, JAPAN.

CLEAT.

Application filed March 6, 1923. Serial No. 623,278.

To all whom it may concern:

Be it known that I, WILLIAM WALLACE CAMPBELL, a subject of the King of Great Britain, and residing in Yokohama, Japan, have invented a new and Improved Cleat, of which the following is a description.

My invention relates to a cleat and while the same is adapted for use generally as a cleat, it is more particularly intended for use on a sail boat for securing a sheet or like rope for which purpose the cleat has particular advantages in that it may be caused to securely hold the rope against the tension on the outboard end and cause said tension to bring about a clamping action of the cleat on the inboard end of the rope while at the same time said inboard end may be released or cast off to permit the sheet to run freely through the cleat and pay out or to permit the quick freeing of the sheet.

Reference is to be had to the accompanying drawings forming a part of this specification, it being understood that the drawings are merely illustrative of one example of the invention.

Figure 1 is a front elevation of a cleat embodying my invention showing the same in place, a portion of the cleat being broken away, the view showing the inboard end of the sheet in clamped position;

Figure 2 is a view similar to Figure 1 but showing the inboard end of the sheet released from the clamping action of the cleat to permit the sheet to pay out;

Figure 3 is a transverse vertical section as indicated by the line 3—3 of Figure 1.

In practice my improved cleat may be mounted on any suitable support. In the example I have shown the cleat secured to a vertical support 10 which may represent the gunwale of a boat. Through said support 10 is a hole 11 for the running of the outboard end 12 of a rope 13 which may represent the sheet of a sail. The numeral 14 indicates the inboard end or free end of the sheet or other rope.

My improved cleat has a base 15 in the form of essentially a flat plate adapted to be suitably fastened as by screws 16 to the support 10. The cleat proper consists of an element 17 having trunnions 18 and rockable in a bearing 19 integral with or otherwise rigid with the base 15. The element 17 constitutes the clamping member of my improved cleat and said element terminates

at its free end in a horn 20 offset at an angle to the general plane of the cleat so that the sheet or other rope 13 may be readily entered beneath said horn 20 and passed inwardly beneath element 17. A transverse hole 21 is formed in the element 17 adjacent the base of the offset horn 20 so as to be partly in register with the transverse hole 11 of the fixed support 10. Also, on the element 17 is a horn 22 adjacent to the hole 21 between said hole and the pivoted end of the element 17 and said horn 22 is disposed in the opposite direction to that of the horn 20.

With the described construction the rope 13 may be variously bent about the cleat members. I have shown said rope 13 as bent about the horn 22 with the outboard end 12 passed through the hole 21 and then through the hole 11 while the inboard end or free end 14 of the sheet passes from the horn 22 beneath the element 17 adjacent to the base of the horn 20 and passing over the outboard end 12 at the inside of the support 10 between said support and the cleat element 17. With the described adjustment of the sheet it will be obvious that the tension on the outboard end 12 will by reason of the bend of the sheet about the horn 22 tend to draw the element 17 toward the support 10, thereby causing the element 17 to clamp the free end 14 of the sheet tightly between said element 17 and the support 10.

The holding action of the cleat on the free end 14 is due also to the fact that when said free end is brought beneath the horn 20 and toward the pivoted end of the element 17, said free end becomes jambed, the tension on the outboard end 12 being effective to cause a clamping action on the said jambed free end 14. The clamping and jamming of the free end 14 will prevent running of the sheet but nevertheless said free end may be quickly released from the clamping action by drawing said free end outwardly toward the terminal of horn 20, the deflection of which horn prevents binding action of said horn on said free end of the sheet.

I would state in conclusion that while the illustrated example constitutes a practical embodiment of my invention, I do not limit myself strictly to the exact details herein illustrated, since, manifestly, the same can be considerably varied without departure

from the spirit of the invention as defined in the appended claims.

Having thus described my invention, I claim:—

5. 1. As a new article of manufacture, a cleat of the class described comprising a base to secure the cleat in position, a clamping element pivotally mounted on said base and adapted to receive a rope therebeneath, 10 the free terminal end of said element being in the form of a horn deflected from the general plane of the cleat, said element having a transverse hole therethrough adjacent to the base of said horn, and a second horn

on said element between said hole and the pivoted end of the element and disposed in the opposite direction from said terminal horn.

2. As a new article of manufacture, a cleat of the class described, including a rope clamping element pivotally mounted at one end and having a transverse hole therethrough; together with a horn on said pivoted element between said hole and the pivoted end thereof and disposed in the direction of said pivoted end.

WILLIAM WALLACE CAMPBELL.
